DUST EXTRACTION APPARATUS

Ernest Coffin and Félix Frédéric Ruau,
Deptford, London, EnglandApplication February 5, 1934, Serial No. 709,882
In Great Britain February 11, 1933

6 Claims. (Cl. 131—39)

This invention is for improvements in or relating to dust extraction apparatus for use on machines handling dusty material, for example, tobacco feeding apparatus such as is used on cigarette making machines or the like.

The object of the invention is to provide improved means whereby dust from the material may be removed from the machine more efficiently than has hitherto been possible and without removing any of the useful portions of the material in question.

In the case of a tobacco feeding apparatus for a cigarette machine, the invention is preferably applied to operate on the tobacco at the point where the tobacco is finally discharged (usually by means of a picker roller operating on a carded distributor) from the feeding apparatus, and in this case it is of great importance that there should not be any surfaces on which the dust 10 may accumulate and from which it might drop periodically and spoil the resulting cigarettes.

It has previously been customary to shroud the tobacco picking roller in order to collect the dust, but it is found in practice that the dust is inclined to adhere very firmly to such shrouds, particularly when the dust is damp.

The invention eliminates all shrouds and such surfaces which are in close proximity to the rotating picker roller are designed, for instance, by 20 making them rotatable to avoid any accumulation.

It is also found that by dispensing with the customary shroud, the dust collected is kept much more free of actual particles of long or short 30 tobacco which it is not desired to extract with the dust than in the machines hitherto used.

The present invention consists of a dust extraction device for machines handling dusty material comprising dust arresting surfaces situated 40 at the points where the dust is principally raised (e. g. near the picker rollers of tobacco feeding apparatus) means for scraping or otherwise cleaning said surfaces and suction means for carrying the dust away. Preferably the dust arresting surfaces are movable in which case they are conveniently formed as rollers.

The invention will be more particularly described with reference to the accompanying drawings in which:—

Figure 1 is a diagram of a tobacco feeding apparatus showing the invention applied thereto.

Figure 2 is a sectional elevation of a part of Figure 1 showing the invention in more detail.

Figure 3 is a side view of another portion of the

apparatus constructed in accordance with the invention.

Figure 4 is an end elevation of Figure 3.

Figure 5 is a view of a detail.

Figure 6 is a bottom view of Figure 5.

Like references refer to like parts throughout the specification and drawings.

Referring to Figure 1 tobacco is fed from a hopper 1 to a combing roller 2 above which is located a brushing roller 3 to evenly distribute the 10 tobacco over the surface of the combing roller 2.

Located in front of and beneath the combing roller 2 is a distributor in the form of a carded roller 4 and the tobacco on the combing roller is picked from the surface thereof by a rotating 15 roller 5 and showered on to the distributor 4.

The distributor 4 carries the tobacco beneath a series of magnets 6 which remove any fragments of iron or steel and the tobacco is then picked from the distributor 4 by another picker 20 roller 7 and showered into the trough 8 of the rod forming mechanism of a cigarette making machine.

Situated in close proximity to the picker roller 7 is a suction conduit 9 the mouth or suction duct 25 9a of which extends parallel to the axis of the picker roller, the conduit being adapted to suck the dust away from the tobacco as explained hereinafter, allowing only the shreds of tobacco to fall into the trough of the cigarette making 30 machine.

In accordance with the present invention dust arresting surfaces are provided which are shown in the drawings as rollers 10 and 11 which are 35 rotatable and arranged so that their surfaces are close to the path swept out by the pins of the picker roller.

The rollers 10 and 11 are geared together by gears 12 and 13, see Figure 4 and are rotated by a ratchet and pawl mechanism, a ratchet 40 14 being secured to the spindle of the roller 11 and operated by a pawl 15 carried on a pivoted arm 16 which is periodically operated by pins 17 carried on a sprocket wheel 18 driven from the main drive of the machine. The end of the duct 9a which is in proximity with the rollers 10 and 11 is arranged to engage with the rollers and is provided with sharp edges 19 and 20 which bear on the rollers and act as scrapers.

The rollers 10 and 11 rotate in such a direction that the surfaces move towards the scrapers 19 and 20 formed by the edges of the duct so that as the dust is deposited it is scraped off and lies in the mouth of the duct and is consequently carried through the suction apparatus with dust 55

in suspension in the neighbourhood of the picker roller 7 and away from the machine.

The suction duct opens into the suction conduit 9 and as this is of considerable length 5 means are provided for equalizing the suction head throughout its length. The means shown in the drawings comprise divisions 21 arranged in the duct to form inlets 22. Each inlet 22 connects with a different section of the conduit 9, 10 which is similarly sub-divided thus connecting different points of the duct immediately with the fan inlet at the remote end of the conduit and in this way the suction head is practically constant whereas with an open conduit there is a 15 continual drop in head roughly proportional to the distance from the fan.

In order to increase the efficiency of the apparatus the inlet from the duct to the conduit may be of restricted or nozzle formation as 20 shown in Figure 5 to increase the velocity of the air.

It is found in a tobacco feeding apparatus of the type above described that dust tends to accumulate on the forward wall 22a of the trough 25 of the cigarette making machine from which it is liable to fall into the filling trough of the machine. In order to prevent the accumulation of dust at this point the forward wall 22a is formed as a movable member and carried on a 30 guide member 23 fixed to the machine frame.

A cam 24 co-operates with a roller 25 carried on a pivoted arm 26 to the opposite end of which is secured a hammer 27, a spring 28 being provided to retain the cam and roller in co-operation. The cam causes the hammer 27 to periodically strike a projection 29 fixed to the front wall 22a and so vibrate the wall when any dust which is adhering thereto is shaken off and is sucked up by the duct 9a together with the dust 40 taken from the rollers 10 and 11 and the suspended dust.

It is to be understood that the above description and application of the invention to a tobacco feeding mechanism is only given by way of 45 example as instead of having rollers it would be possible to effect the desired object by using fixed dust arresting surfaces having movable scrapers co-operated therewith and further although the invention has been described as applying to the final picker of the machine, it is 50 equally applicable to other pickers or any points where the operation of the machine produces a quantity of dust.

What we claim as our invention and desire to 55 secure by Letters Patent is:—

1. In apparatus for feeding tobacco, the combination with a carded conveyor for the tobacco, of a picker roller having projections thereon for removing the tobacco from said conveyor, a pair 60 of movable dust arresting elements located adjacent said picker roller and spaced apart from each other to provide a free passage between said elements, and a suction duct extending lengthwise of said elements connected at one end with a 65 source of suction and at the other end engaging the dust arresting elements and forming a continuation of the passage formed between said elements.

2. In apparatus for feeding tobacco, the com-

bination with a carded conveyor for the tobacco, of a picker roller having projections thereon for removing the tobacco from said conveyor, a pair of movable dust arresting elements located adjacent said picker roller and spaced apart from each other to provide a free passage between said elements, and a suction duct extending lengthwise of said elements connected at one end with a source of suction and at the other end engaging the dust arresting elements and forming a continuation of the passage formed between said elements, said suction duct having partitions which divide it lengthwise and which equalize the suction along the duct. 10

3. In apparatus for feeding tobacco, the combination with a carded conveyor for the tobacco, of a picker roller having projections thereon for removing the tobacco from said conveyor, a pair of movable dust arresting elements located adjacent said picker roller and spaced apart from each other to provide a free passage between said elements, and a suction duct of nozzle formation connected at its larger end with a source of suction, and at its restricted end engaging the dust arresting elements and forming a continuation 20 of the passage formed between said elements. 25

4. In apparatus for feeding tobacco, the combination with a carded conveyor for the tobacco, of a picker roller having projections thereon for removing the tobacco from said conveyor, a pair of 30 movable dust arresting elements located adjacent said picker roller and spaced apart from each other to provide a free passage between said elements, and a suction duct of nozzle formation connected at its larger end with a source of suction, and at its restricted end engaging the dust 35 arresting elements and forming a continuation of the passage formed between said elements, said suction duct having partitions which divide it lengthwise and which equalize the suction along 40 the duct.

5. In apparatus for feeding tobacco, the combination with a carded conveyor for the tobacco, of a picker roller having projections thereon for removing the tobacco from said conveyor, a pair 45 of rotatable rollers located adjacent said picker roller and spaced apart from and geared to each other, a ratchet wheel fixed to one of said rollers, a pawl to engage with and operate said ratchet, and a suction duct connected at one end with a 50 source of suction and at the other end engaging said rollers and forming a continuation of the space formed between the rollers.

6. In apparatus for feeding tobacco, the combination with a carded conveyor for the tobacco, of a picker roller having projections thereon for removing the tobacco from said conveyor, a pair of rotatable rollers located adjacent said picker roller and spaced apart from and geared to each other, a ratchet wheel fixed to one of said rollers, 60 a pawl to engage with and operate said ratchet, and a suction duct connected at one end with a source of suction and at the other end engaging said rollers and forming a continuation of the 65 space formed between the rollers, said suction duct having partitions which divide it lengthwise and which equalize the suction along the duct.

FÉLIX FRÉDÉRIC RUAU,
ERNEST COFFIN.
